UNITED STATES PATENT OFFICE.

MILTON F. WILLIAMS, OF ST. LOUIS, MISSOURI, ASSIGNOR TO WILLIAMS PATENT CRUSHER AND PULVERIZER COMPANY, OF ST. LOUIS, MISSOURI, A CORPORATION OF MISSOURI.

METHOD OF REDUCING FIBROUS SHEET MATERIAL.

1,417,961.

Specification of Letters Patent. Patented May 30, 1922.

Application filed October 7, 1920. Serial No. 415,324.

To all whom it may concern:

Be it known that I, MILTON F. WILLIAMS, a citizen of the United States, residing at St. Louis, State of Missouri, have invented 5 certain new and useful Improvements in Methods of Reducing Fibrous Sheet Material, of which the following is a specification.

This invention relates to certain new and 10 useful improvements in the method of reducing fibrous sheet material such as sulphite paper board, the peculiarities of which will be hereinafter fully described and claimed.

The main object of my invention is to reduce 15 sulphite paper board or like fibrous material from its comparatively hard pressed sheet condition to a fluffy, finely divided, comminuted state for further preparation in the manufacture of paper.

20 In the accompanying drawing on which reference letters are used to identify the parts described, the single view represents, partly in perspective, a diagrammatic view of the preferred means for carrying out this 25 method.

The letter A designates a shredding machine 30 in the form of a grinder having rotary pivoted hammers B formed by rectangular bar steel; the outer end of each is chamfered off to allow for clearance in operation, and the front forward face is drawn forward and sharpened to present a cutting edge the length of which corresponds to the thickness of the bar, and is adapted to slice a 35 thin elongated sliver from the board or sheet of material that is passed between compression rollers C and D, and extends inward over the edge of a cutter bar D into the path of the said hammers, whereby said

40 slivers of the material are first cut upon the cutter bar and then are carried down for further action in connection with a perforated cage E. As said slivers are forced outward through the perforations in the 45 cage they are cut crosswise into shorter pieces, and are also further divided lengthwise by the cutting edges of the rotary hammers operating in close proximity to said cage.

50 The material thus divided, passes through the cage as indicated in the figure, and is

acted upon by a blast of air entering at F and carried along outward from beneath the shredding machine into a pipe G that is connected to an exhaust fan H. The fan has 55 a discharge pipe I that rises from the outlet of the fan vertically, and is bent over at its upper end into tangential connection with a cyclone collector J of the usual or any approved style, from the bottom end of which 60 it is discharged by a pipe K to the floor or a suitable receptacle. The outlet end of the cyclone collector is connected by a pipe L with a rotary or other suitable form of collector M, adapted to catch the finest particles and dust that is discharged from the cyclone collector. 65

After the mechanical division of the sulphite paper board into slivers by the cutting edges of the rotary hammers B, and the 70 further division of said slivers in connection with the cage E, the air blast takes up the finely divided material and, by its action upon the same, further separates the particles of the fiber, and in sending it upward into the cyclone collector, causes it to become fluffy and lose its solid, mechanically divided condition. The longer fibrous portions of the material are discharged from the cyclone collector through the outlet pipe 75 K, while the dust and the finest particles are discharged through the outlet L and collected by the rotary collector M. In this fluffy, cotton-like condition of the sulphite paper board or similar material, it is very 80 readily acted upon in the further preparation of print paper, and for other purposes in which such changed condition of the material is desirable. 85

I claim:

The herein described method of reducing fibrous sheet material, the same consisting in shredding it into slivers, then dividing said slivers lengthwise and crosswise, then subjecting the comminuted fiber to air currents, and then separating the dust and smallest pieces from the relatively longer, 90 fluffy fibrous portions. 95

In testimony whereof I have affixed my signature.

MILTON F. WILLIAMS.
